UNITED STATES PATENT OFFICE

HENRY A. STANG, OF MINNEAPOLIS, MINNESOTA

BRUSH HOLDER

Application filed January 25, 1928. Serial No. 83,532.

My invention relates to brush holders and has for its object to provide a tray upon which a brush may be placed, which tray is adapted to be detachably mounted on a pail 5 with the front portion thereof projecting inwardly from the rim of the pail.

Another object resides in turning up the edges of said tray along the two ends and along the back thereof leaving the front of 10 the tray unobstructed, and in tilting or inclining said tray forwardly so that the drip from a brush supported on said tray may drain back into the pail.

A still further object resides in providing 15 a pair of clips for attaching said tray to the pail, each of which clips consist of a base, and two legs adapted to straddle the rim of the pail and to clamp upon the body of the pail, and in further pivotally attaching said clips 20 to the bottom of the tray so that the same may swivel to conform to the curvature of any selected pail.

Another object of the invention resides in 25 arranging the clips so that same provide legs for the tray when it is detached from a pail and disposed upon a supporting surface, said legs causing the holder to tilt back and thereby trap any drip from a brush supported thereon.

30 A feature of the invention resides in providing prongs which extend upwardly from the tray and serve to engage a brush and hold it in position on the tray.

Another feature of the invention resides 35 in the adaptability of the brush holder as a brush wiper.

With the foregoing and other objects in view, which will appear in the following description, the invention resides in the novel 40 combination and arrangement of parts and in the details of construction hereinafter described and claimed.

In the drawing illustrating my invention in one form:

45 Fig. 1 is a perspective view of a brush holder embodying my invention, the same being shown as applied to a pail.

50 Fig. 2 is an elevational view of the structure shown in Fig. 1 illustrating a brush positioned upon the holder.

Fig. 3 is an enlarged fragmentary plan view illustrating the application of the holder to pails of various sizes.

Fig. 4 is an elevational view showing the use of the holder for supporting a brush 55 when said holder is detached from a pail and disposed upon a supporting surface.

Fig. 5 is a perspective view in detail, of one 60 of the clips used with my improved brush holder.

In the use of brushes for paperhanging, painting or other purposes, considerable inconvenience is encountered when it becomes desirable to lay down the brush. When it is attempted to lay the brush across the rim of 65 a pail or can, the liquid within the brush flows down along the outside of the pail to the support upon which the pail stands. At the same time the handle of the brush bears upon the rim of the pail where surplus liquid 70 has been left in previously wiping out said brush with the result that said handle becomes soiled. When a stick or other article is placed across the pail similar results occur and in addition the mouth of the pail is obstructed 75 so as to prevent ready access thereto. My invention overcomes these difficulties and objections by providing a holder which receives the drip from the brush and discharges it into the pail and which may be readily 80 attached to pails of any dimensions to hold the same supported thereon, or which may support the brush independent of the pail and collect and hold the drip from said brush.

For the purpose of illustrating the application 85 of my invention I have shown in the drawings a pail A having the usual body 10, beaded rim 11, bottom 12, and bail 13 pivoted to ears 14 on the body 10.

The brush holder proper indicated in its en- 90 tirety at B consists of a tray 15 of rectangular formation and preferably constructed of sheet metal. The edges 16, 17 and 18 of said tray are upturned along the two ends and back the fourth or front edge 19 being left 95 undisturbed. The structure so formed serves to catch the drip from a brush placed thereon as indicated in Fig. 2 and to drain said drip into the pail A. For this purpose the holder B is positioned upon the rim 11 with the edge 100

19 disposed inwardly therefrom and the outer edge 17 disposed outwardly of said rim. By tilting the tray 15 so that edge 19 rests beneath the rim 11 the desired result may be accomplished.

5 For attaching the holder B to the pail A, I employ two identical clips 20 and 21 one of which is shown in detail in Fig. 5. These clips are constructed of a metal strap which is bent along a line 22 and doubled up to form a base 23 comprising two overlapping portions 24 and 25. The portion 24 is bent along a line 26 to form a leg 27 while the portion 25 is somewhat longer than the portion 24, 10 being similarly bent along a line 29 to form a second and shorter leg 28 spaced from the leg 27. This latter leg terminates in a curved tip 30 being relatively close to the leg 27. Each of the two clips 20 and 21 is riveted to 15 the tray 15 by means of a rivet 31 which passes through a hole 32 in the base 23 and through the tray 15. These rivets are sufficiently tight to hold the clips firmly attached to the tray 20 and yet allow the clips to swivel or pivot upon 25 the same.

In attaching the holder to a pail such as shown at A in Fig. 3 the procedure is as follows: The clips 20 and 21 are first turned on rivets 31 to correspond with the curvature of the selected pail, as indicated in dotted lines at 33 in Fig. 3. The structure is then presented to the pail with the legs 27 disposed against the outside of the body 10 thereof at the rim. By applying downward pressure upon the holder the legs 27 and 28 are spread apart by the rim 11 which becomes lodged between said legs with the protruding end of the clip portion 25 seated thereon. Yieldingly gripping the body 10 of the pail, 30 the legs 27 and 28 of the clips 20 and 21 clamp the holder structure on the pail. It will be noted that the legs 27 and 28 of each clip issue obliquely from the base 23. This has the effect of holding the tray 15 tilted so that the 35 drip from a brush thereon drains over edge 19 and back into the pail. It will also be noted that said edge 19 provides an effective wiping edge for a brush after it has been dipped into the liquid in the pail.

40 50 For the purpose of illustration, I have shown a brush 35 of ordinary construction. In use said brush is placed upon the tray 15 with the handle 36 resting upon the upturned edge 17 and the bristles 37 overhanging the edge 19. The brush is held in this manner, with the back thereof clear of the upper surface of tray 15, by means of two upstanding prongs 38 and 39 which are anchored to the tray 15. These prongs penetrate the bristles 45 55 60 65 70 75 80 85 90 95 100 105 110 115 120 125 130 135 140 145 150 155 160 165 170 175 180 185 190 195 200 205 210 215 220 225 230 235 240 245 250 255 260 tending portion of said base and said tray for swivelly connecting said clips to said tray.

5. A brush holder for application to a pail comprising a tray, a pair of clips attached to said tray, said clips having surfaces adapted to contact with the curved surface of the pail, and a pivot for one of said clips permitting the relative movement of the clips to vary the angularity between the contacting surfaces thereof.

10. 6. A brush holder for application to a pail comprising a tray, a pair of clips attached to said tray, said clips having surfaces adapted to contact with the pail and to intersect radii drawn through the centers thereof at right angles, and a connection for one of said clips permitting the surface thereof to be shifted to occupy the same position with respect to the radii of pails having different curvatures.

15. 20. In testimony whereof, I have signed my name to this specification.

HENRY A. STANG.
